CLAIM

The ornamental design for an apparel fixation device, as shown and described.

DESCRIPTION

FIG. 1 is a top, left perspective view of an apparel fixation device in accordance with the subject technology.

FIG. 2 is a bottom, left perspective view of the apparel fixation device of FIG. 1.

FIG. 3 is a front view of the apparel fixation device of FIG. 1.

FIG. 4 is a rear view of the apparel fixation device of FIG. 1.

FIG. 5 is a left side view of the apparel fixation device of FIG. 1.

FIG. 6 is a top view of the apparel fixation device of FIG. 1; and,

FIG. 7 is a bottom view of the apparel fixation device of FIG. 1.

Right side views are omitted, the right side views being a mirror image of the left side views shown herein.

The purpose of the broken lines shown in the drawings is to denote environmental structure that forms no part of the claimed design. Therefore the elephant design shown in broken lines on FIGS. 1 and 6 forms no part of the claimed design.
